UNITED STATES PATENT OFFICE

WALTER B. GORR, OF ERIE, PENNSYLVANIA, ASSIGNOR TO SPINNER ENGINE COMPANY, OF ERIE, PENNSYLVANIA, A CORPORATION OF PENNSYLVANIA

STEAM ENGINE

Application filed December 7, 1927. Serial No. 238,426.

This invention is designed to improve the cross head guide construction. It is desirable in engines to have the cross head guide exactly in alinement with the axis of the cylinder so that the reciprocating parts may move freely and without binding. In constructing engines forming the parts so as to give perfect alinement between the cylinder and the guides has given difficulty particularly with 5 relation to cross head guides having open sides giving free access to the cross head. With such open guides it is desirable to reverse the direction which the guides face with the reversal of the running direction of the 10 engine so that the wearing surface of the guide will at all times be the major surface. With the present invention the cross head guide is so formed as to be positively alined with the cylinder and also is so arranged 15 that it may be readily reversed thus forming the guide for engines running in either direction. Features and details of the invention will appear more fully from the specification and claims.

25 A preferable embodiment of the invention is illustrated in the accompanying drawings as follows:—

Fig. 1 shows a side elevation of an engine, partly in section.

30 Fig. 2 a front elevation of the engine.

Fig. 3 a section on the line 3—3 in Fig. 4.

Fig. 4 a section on the line 4—4 in Fig. 3.

1 marks the main frame of the engine, 2 the cylinder, 3 the cylinder head, and 4 a 35 cross head connecting frame. This connecting frame 4 has a flange 5 which rests on a seat 6 at the upper end of the main frame and is secured thereon by screws 7. The upper end of the connection has a flanged seat

40 8 with a cylindrical shoulder 9 and the flange is seated on a seat 10 at the end of the head 3, the head having a cylindrical internal shoulder 11 receiving the shoulder 9. The cylinder head 3 likewise has an annular shoulder 13 fitting a shoulder 14. A cross head 45 guide 15 of cylindrical form has a cylindrical main surface concentric with the shoulder 9, being preferably machined with the same set up. A cross head 16 has its main wearing 50 surface cylindrical and conforming to the

cross head guide 15. The cross head 16 has the extending edges 16^a and guide bars 17 secured to the guide frame extend over the extended edges 16^a, thus holding the cross head to its seat. A piston rod 18 extends 55 from a piston 19 through a gland 20 in the cylinder head. A connecting rod 21 extends from the cross head to the crank, the crank being shown in dotted lines.

It will be noted with this construction that 60 the cross head guide is open at the front side giving direct access to the cross head; that the guide frame may be machined with a cylindrical guide surface and that the cylindrical shoulders 9 are exactly concentric and the surface of the seat 8 is in a plane directly at right angles to the axis so that the ordinary turning operation perfectly alines these parts, in fact, it is difficult to get them out of alinement. The same may be said of the 65 cylinder head, these parts being turned in the ordinary turning operation and the resulting parts necessarily being concentric and in alinement so that when the head is placed on the cylinder it is again concentric 70 and in alinement with the cylinder. Thus all parts are in exact alinement without careful cross checking in the machine, the ordinary turning operation accomplishing this 75 result. The cross head guide frame may be 80 rotated 180° about its axis so that the pressure on the cross head guide surface will follow the cylindrical or major guiding surface in the running of the engine, this pressure being due to the angularity of the connecting rod. The structure, as will be noted, permits of a frame which may be readily uncovered as shown to disclose the operating parts.

While I have shown a separate cylinder 90 head 3 between the seat 9 and the cylinder walls I do not wish to be limited to a construction in which such part is interposed between the cylinder proper and the supporting seat.

95 What I claim as new is:—

1. In an engine, the combination of a main frame; a cylinder; a connecting frame between the cylinder and main frame having a cylindrical cross head guiding surface at 100

one side, an alining and centering seat for the cylinder, and a support which rests on a seat at the upper end of the main frame; a cross head on the guiding surface; and guide plates extending over the cross head.

5 2. In an engine the combination of a main frame; a cylinder; a connecting frame between the cylinder and main frame having a cylindrical cross head guiding surface at one side, an alining and centering seat for the cylinder, and a support which rests on a seat at the upper end of the main frame, said connecting frame being reversible on its axis; a cross head on the guiding surface; and guide plates extending over the cross head.

10 15 In testimony whereof I have hereunto set my hand.

WALTER B. GORR.
